Patented Oct. 20, 1914.

Fig. 1.

UNITED STATES PATENT OFFICE.

EUGENE MACON COLE, OF CHARLOTTE, NORTH CAROLINA.

CULTIVATOR.

1,114,117.

Specification of Letters Patent. Patented Oct. 20, 1914.

Application filed December 7, 1912. Serial No. 735,519.

To all whom it may concern:

Be it known that I, EUGENE M. COLE, a citizen of the United States, residing at Charlotte, in the county of Mecklenburg and State of North Carolina, have invented a new and useful Cultivator, of which the following is a specification.

This invention relates to cultivators, its principal object being to provide a simple, practical, adjustable machine for planting 10 two or more rows of grain or other seeds between the rows of growing crops at one trip.

Another object is to provide a structure 15 of this character having novel means for adjustably supporting the beams carrying the soil engaging elements.

With the foregoing and other objects in view which will appear as the description 20 proceeds, the invention resides in the combination and arrangement of parts and in the details of construction hereinafter described and claimed, it being understood that changes in the precise embodiment of 25 the invention herein disclosed, can be made within the scope of what is claimed, without departing from the spirit of the invention.

In the accompanying drawings the preferred form of the invention has been shown.

30 In said drawings:—Figure 1 is a side elevation of the machine. Fig. 2 is a plan view thereof. Fig. 3 is a rear elevation, the central boot being partly removed. Fig. 4 is a side elevation of the adjusting means employed in connection with the intermediate furrow opener, the cross beam of the structure being shown in section. Fig. 5 is a detail view of the adjusting wedge.

Referring to the figures by characters of 40 reference 1 designates connected longitudinal beams between which is journaled a combined supporting and drive wheel 2. Extending between the front ends of these beams 1 is a clevis 5.

45 Rearwardly diverging handles 12 extend from the rear ends of the beams 1 and fixedly mounted on these beams at points in front of the handles 12 are cross beams 13 and 14, said cross beams being parallel and 50 being provided with longitudinal series of apertures 15. Forwardly converging braces 16 connect the ends of the front beam 13 to the sides of the beams 1 near the front ends thereof and extending under the cross beams 55 13 and 14 are side strips 17 which are secured to the beams 13 and 14 by means of

bolts 18 extending into certain of the openings 15. Thus it will be seen that by removing bolts 18, the side strips 17 can be adjusted toward and from each other and 60 then held in adjusted position by inserting said bolts into the proper openings.

As shown in the drawings, the handles 12 may be provided with suitable braces 26 which, if desired, may be mounted on standards 24 upstanding from the end portions of 65 the beam 14.

A pivot bolt 75 is supported by the beams 1 back of the wheel 2 and mounted to swing on this bolt is a central strip 76 which extends rearwardly and under the cross beam 14. An adjusting bolt 77 extends upwardly from the rear end portion of the strip 76 and projects through the beam 14, said bolt being engaged by a lever nut 78 whereby it 70 can be readily tightened or loosened. A wedge 79 formed as shown at 80, may be inserted between beam 14 and central strip 76 so as to straddle the bolt 77. By then tightening the bolt, the wedge will, 75 obviously, be held against displacement. It will be seen that by forcing the wedge 79 between strip 76 and beam 14, the said strip 76 can be adjusted downwardly. Secured to 80 each of the strips 17 and 76 is a plow standard 81 carrying a furrow opener 82.

As the soil between the rows of crops is sometimes flat and very often concaved or depressed more or less in the center between the rows, it has been found desirable, in the 90 present case, to make the middle opening plow adjustable upwardly and downwardly. The transverse adjustment of the plows of the present machine is also rendered desirable in view of the fact that the distance 95 between rows varies.

It is designed to arrange the intermediate furrow opener some distance back of the side furrow openers. This arrangement allows the side openers to fill in the low places 100 between rows before the intermediate furrow opener is brought into position. This arrangement also serves to keep the openers free of trash.

What is claimed is:—

1. In a machine of the class described, the combination with a cross beam and longitudinal beams connected thereto, of a longitudinal strip pivotally mounted between the longitudinal beams, a furrow opener connected to said strip, an adjusting bolt extending upwardly from the strip and 110

105

through the transverse beam, a forked wedge straddling the bolt and interposed between the strip and cross beam, and means engaging the bolt and the cross beam for binding the wedge between said cross beam and strip.

2. The combination with wheel supported central beams, and a pair of spaced transverse beams supported thereby, of side strips connecting the end portions of the transverse beams and adjustable toward and from

each other, a strip supported between and adjustable upwardly and downwardly relative to the central beams, and furrow openers carried by the respective strips.

15 In testimony that I claim the foregoing as my own, I have hereto affixed my signature in the presence of two witnesses.

EUGENE MACON COLE.

Witnesses:

H. F. WOLFE,
E. A. BROOKS.
